SPRAYING APPARATUS

Henry James Newlin, Birmingham, England

Application February 26, 1935, Serial No. 8,351
In Great Britain January 12, 1935

2 Claims. (Cl. 299—140.1)

This invention relates to spraying apparatus for liquids, of the type in which air and the liquid are fed to a discharge nozzle. It is sometimes required that the spray should be substantially round, whilst at other times it is required to be fan-shaped; and this invention has for its object a spraying apparatus in which the spray can be very readily changed over from one condition to the other and preferably whilst the spraying apparatus is in action.

According to this invention, the flow of air under pressure is controlled so that it can be fed to the nozzle to either produce a round spray or a fan-shaped spray. For this purpose a valve control device is provided which controls the flow of air through two separate conduits leading to the spraying nozzle to produce the round spray or to produce the fan-shaped spray. Preferably when the air is passing through the conduit to effect a fan-shaped spray, the conduit leading the air to form the round spray also remains open. The valve mechanism is conveniently actuated by a single spray control trigger or member, so that the operator can either obtain a round spray or the fan spray by simply operating the trigger which starts and stops and variably controls the spray. The valve mechanism is conveniently in the form of a double valve operated by the trigger, and the arrangement is such that the timing of the opening of the second valve in relation to the first valve is adjustable. The double valve conveniently comprises a directly operated valve which opens the conduit for forming the round spray, and which when operated simultaneously moves the second valve. The seating of the second valve however normally moves simultaneously with the valve so that the second valve, controlling the fan spray, is not opened until the movement of the seating is stopped by a suitable abutment.

Referring to the drawing:—

Figure 1 is a cross sectional elevation of a spraying gun constructed according to this invention, and

Figure 2 shows a modified form of valve mechanism.

According to a convenient embodiment of the invention, the apparatus comprises the frame 1 of a spraying gun on which is mounted a control trigger 2. The needle valve 3 controlling the liquid coacts with a trigger 2 intermediate its pivot axis and the outer end or finger grip of the trigger. The upper portion of the gun frame is bored longitudinally in a direction which inclines inwardly from the back end of the gun to

the nozzle end. A bush 4 is fixed in this bore by screwed connection at its rear end. A second bush 5 is also fitted in alignment in front of the first bush and a valve seating 6 is located between the two bushes. A mushroom head valve 7 coacts with this seating and is formed on the valve stem which is screwed to the cylindrical slide block 8. A cup shaped washer 9 is fixed between this block and a collar on the valve stem to form an air seal in the bush 4. The trigger 2 has an arm 10 projecting beyond the pivot axis which coacts with the sliding block, so that when the trigger is actuated the valve 7 is moved axially. The compressed air passes through a conduit 11 in the body of the gun and leads to the chamber 12 at the back of the valve seating 6. The stem 13 of the valve is extended beyond the aforementioned first valve 7 and a second valve 14 is provided thereon. This second valve coacts with a conical seating formed on the inside of a seating ring 15, slidably mounted in the inner sleeve bushing aforementioned. Two separate air branch conduits 16 and 17 pass to the nozzle. Perforations are formed in the wall of the bush 5 on the outlet side of the first mentioned valve 7 and these perforations communicate with a cylindrical recess 18 around the bush, from which passes the conduit 16 which leads to an inner annular chamber 19 at the front of the frame on which the spraying nozzle 20 is fixed. When the trigger is operated the first valve 7 is opened and thus allows air to pass to the nozzle for producing the round spray. The second valve 14 lies on the outlet side of the said perforations so that an air chamber 20 is provided behind the second valve 14 and its seating. The second valve is simultaneously moved with the first valve, but the air pressure in the chamber 20 causes the seating to slide with the valve and consequently the second valve is not opened. An adjustable stop is provided against which the valve seating 15 moves, thus preventing the seating moving with the valve head. The air can thus pass through the second valve 14 along the bush 5 to the axially arranged conduit 17 leading to an outer annular chamber 22 at the nozzle end of the gun frame. A spiral spring 23 bears against the head of the second valve to normally press the valves 14 and 7 into the closed positions. The adjustable stop conveniently comprises a rotatable pin 29 having a round abutment head 30, one half of which is cut away. By rotating this pin, the movement of the slideable valve seating 15 is adjustably limited, so that the second valve 14 can be arranged to open at

any time in relation to the opening of the first valve 7. Thus at one end of the adjustment the fan shaped spray is almost immediately obtained as both conduits 16 and 17 leading to the nozzle are opened one immediately or almost immediately after the other. At the other end of the adjustment, the round spray can be fed by a more fully opened liquid needle valve 3 with the full air pressure without the fan shaped spray being obtained. The nozzle end of the gun frame has thus two annular chambers 19 and 22 which are closed by a screwed distributor sleeve 24 receiving the nozzle. Openings are provided in the front of this sleeve 24 leading to appropriate channels in or around the nozzle and in the air cap to give the spray. The adjustable pin aforementioned may be mounted in a bush 25 screwed on the frame 1 and the outer end of the pin may be fitted with a head 26 which coacts with spring controlled or other stops to facilitate quick adjustment to obtain any desired condition of spray.

According to a modified form of the invention, as shown by Figure 2, the second valve 14 aforementioned may be substituted by a ball 27 which beds on the slidable seating sleeve 15a aforementioned. This slidable seating sleeve may coact with an adjustable stop 28 screwed in the frame axially of the sliding seating.

With this construction and with the setting shown by Figure 1, when the trigger 2 is first moved, the valve 7a is opened and air is fed to the nozzle by way of the conduit 16a. A small opening of the valve 7a allows air to flow at substantially full pressure. The needle valve 3a is also opened, but the arrangement is such that it is opened after the air valve is opened. On the further movement of the trigger the liquid valve is further opened, thereby giving a variable round spray. On the further movement of the trigger the seat 15a moves against the stop 28 and air flows to produce a fan-shaped spray. By adjusting the stop 28, the fan spray can be produced at any suitable point of the trigger movement, and the relationship of the opening of the needle valve can be arranged to provide for a variable fan spray.

I claim:

1. Apparatus for spraying liquids or other material, comprising a frame, a spraying head carried by the frame, at which occurs, alternatively, round and fan shaped sprays, a needle discharge valve coacting with a seating in the spraying head for the material to be sprayed, a hand control device for moving the needle valve, an air valve slidably mounted in an air chamber in the frame, an air main feed conduit leading to one

side of the air valve, an air chamber on the other side of the said valve, a branch air conduit passing from such chamber and leading to an annular chamber at the spraying head for supplying air to produce a round spray, a slidably mounted valve seating and valve thereon forming a plunger closure at one end of the said air chamber and arranged axially of the first mentioned valve, means interconnecting the said two valves so that when the first mentioned valve is opened the second mentioned valve is moved axially followed by the seating under air pressure so that this second valve is not opened, an adjustable stop for limiting the movement of the said slidable valve seat and to open the second valve, an air branch conduit opened to the said air chamber by the second mentioned valve and leading to a second annular chamber at the spraying head for supplying air to produce a fan-shaped spray, and means for actuating the valves by the said hand control device to open the valves successively.

2. Apparatus for spraying liquids or other material, comprising a frame, a spraying head, carried by the frame, at which occurs, alternatively, round and fan shaped sprays, a needle discharge valve coacting with a seating in the spraying head for the material to be sprayed, a trigger pivoted to the frame for moving the needle valve, an air valve slidably mounted in an air chamber in the frame, an air main feed conduit leading to one side of the air valve, an air chamber on the other side of the said valve, a branch air conduit passing from such chamber and leading to an annulus at the spraying head for supplying air to produce a round spray, a slidably mounted valve seating and valve thereon forming a plunger closure at one end of the said air chamber and arranged axially of the first mentioned valve, means interconnecting the said two valves so that when the first mentioned valve is opened the second mentioned valve is moved axially followed by the seating under air pressure so that this second valve is not opened, an adjustable stop for limiting the movement of the said slidable valve seat and to thereby open the valve, an air branch conduit opened to the said air chamber by the second mentioned valve and leading to a second annulus at the spraying head for supplying air to produce a fan-shaped spray, and means connecting the said trigger and the first mentioned valve so that the trigger successively opens the valves and controls the feed of the material to be sprayed and the air feed to form successively either a round or fan-shaped spray.
